Patented Dec. 16, 1913.

UNITED STATES PATENT OFFICE.

EDWARD K. PARKER, OF SANTA BARBARA, CALIFORNIA.

ELECTRIC PNEUMATIC-PRESSURE CONTROLLER.

1,081,693.

Specification of Letters Patent. Patented Dec. 16, 1913.

Application filed August 12, 1912. Serial No. 714,584.

To all whom it may concern:

Be it known that I, EDWARD K. PARKER, a citizen of the United States, and resident of Santa Barbara, in the county of Santa Barbara and State of California, have invented new and useful Improvements in Electric Pneumatic-Pressure Controllers, of which the following is a specification.

My invention relates to a control for use in pneumatic pressure and power systems, and more particularly it relates to electrically operated means for controlling the valve in such systems, whereby the pneumatic pressure or power may be shut off or let on instantaneously at the will of the operator, or shut off automatically at a predetermined degree of pressure.

While my invention is peculiarly adapted for automatically shutting off the pressure in pneumatic pressure apparatus, when the pressure reaches a predetermined point, it will be understood that the invention is by no means limited to such use.

In the drawings hereto annexed, which illustrate certain embodiments of my invention,—Figure 1 is a diagrammatic view, partly in elevation and partly in section, of an automatically controlled pneumatic pressure apparatus; Fig. 2 is a vertical, central section through the pressure gage shown in Fig. 1.

Referring to the drawings, A is an air-tight casing upon which is mounted a conduit B having an inlet port b and an outlet port b', and forming in effect a part of the casing. Within said conduit B and located between said ports b and b' is a valve seat b² for the valve C, said valve being slidably mounted in said conduit and pivotally connected at one end to a lever D, which is pivoted within said casing A at d' and provided with a stud d. Mounted upon the bottom of said casing A in any suitable manner is an electro-magnet E consisting of an armature e, a guide-tube e' and a coil e². A spring e³ is located within said tube e' between said armature and the bottom of said tube; and said armature e is provided at its top with a hook or projection e⁴ and a finger e⁵. Upon a side wall of said casing A is mounted another electro-magnet F consisting of an armature f, a guide-tube f' and a coil f². A spring f³ is located within said tube f' between said armature and the bottom of said tube; and said armature is provided at its top with a hook or projection f⁴. Slidably

mounted upon an inner wall of said casing is a bolt G provided near one end with a stud g, said bolt adapted to coöperate with said armature f to lock the valve C in open position as presently to be described.

A pressure gage H is mounted in the usual manner upon an extension B' on the conduit B, and is provided with the usual dial h, index hand h' and glass front h². Said glass front has a central opening in which is rotatably mounted a metallic plug h³, preferably provided with a knob or handle x on its outer end and having a metallic indicator h⁴ upon its inner end, said indicator being 70 preferably hooked, or curved inward, at its free end as clearly shown in Fig. 2. A metal strip h⁵ serves as a metallic connection between said plug h³ and the extension B' upon which the gage is mounted. It will be 75 understood that the index hand h' is in metallic connection with the extension B' through its pivot pin and the dial, and the casing of the gage.

Suitable electric connections for energizing the electro-magnets F and E and actuating the device are provided as follows: For energizing the electro-magnet F the connection is, by the wire J' from the strip h⁵ to one end of the coil f²; by the wire J² from the other end of said coil f² to the binding post k of the battery K; from the binding post K' by the wire J³ to the casing A, which is in metallic connection with the index hand h' through pipes B, B' and gage casing H. For energizing the electro-magnet E, the connection is from the binding post K' by wire J⁴ to the contact point L, forming one end of a normally open switch; from the other contact point L' of said switch by the wire J⁵ to one end of the coil e², and by the wire J⁶ from the other end of said coil e² to the binding post k.

The operation of the device is as follows: The operator desiring for example to inflate an automobile tire and automatically to shut off the pneumatic pressure, say at a pressure of 30 pounds to the square inch, sets the indicator h⁴ at 30 upon the gage dial. The switch comprising contacts L and L' is 100 closed, thereby closing the circuit which energizes the electro-magnet E and causing the armature e to be drawn down from its normal position shown in dotted lines in Fig. 1 to the position shown in full lines in 110 said figure. Upon its downward passage the hook e⁴ engages the stud d of the lever D

and draws said lever downward, thus opening the valve C. It will be observed that the hook e^4 is of such length that it has traveled a considerable distance upon its downward 5 passage before it engages the stud d so that it strikes sharply against said stud and draws the lever D quickly downward. The armature e , and consequently the valve C, is locked and retained in its depressed position 10 by the sliding bolt G which is pushed forward by the armature f , actuated by the spring f^3 , into engagement with the end of finger e^5 .

The valve being thus opened and locked in 15 open position, the air or gas from a suitable source of pneumatic pressure (not shown) enters by the intake port b and issues from the outlet port b' . The pressure causes the index hand h' to travel over the face of the 20 dial in the usual manner until it comes in contact with the hooked end of the indicator h^4 , thus closing the circuit which operates the electro-magnet F. When said electro-magnet is thus energized the armature f is drawn backward, and in its backward movement the projection f^4 engages the stud g and withdraws the bolt G from engagement with finger e^5 permitting the spring e^3 to return the armature e to its 25 normal or dotted line position shown in Fig. 1, thus reseating the valve.

It will be clear that as the projection f^4 like the hook e^4 is relatively long, it has traversed a considerable distance upon its 30 backward movement before it engages the stud g , and that therefore it strikes sharply against said stud and quickly withdraws the bolt G.

It will be observed that not only the valve 40 C, but the entire electrically controlled means for opening and closing the valve are contained within the valve casing which is tight against leakage and closed to the atmosphere except through the inlet port b and 45 through the valve. Thus, by this construction all danger of leakage due to defective packing or bushings is eliminated and furthermore the device may be made in very compact form.

50 I claim:

1. In a device of the class described, a casing having an inlet port and an outlet port, a valve, a seat for said valve located between said ports, a lever pivoted in said 55 casing, a connection between said lever and said valve, an electro-magnet mounted on said casing and having a spring-pressed armature adapted to coöperate with said lever to open and close said valve, a bolt, 60 another electro-magnet mounted on said casing having a spring-pressed armature adapted to coöperate with said bolt to lock said valve in open position, a pressure gage

mounted on said casing and having a rotatably mounted indicator and an index hand, 65 and an electrical connection between said last named electro-magnet and said gage whereby when said index hand makes contact with said indicator said armature co-operates with said bolt to unlock said valve. 70

2. In a device of the class described, a casing having an inlet port and an outlet port, a valve, a seat for said valve located between said ports, a lever pivoted in said casing, a connection between said lever and 75 said valve, an electro-magnet mounted on said casing and having a spring-pressed armature provided with a projection, said projection adapted to coöperate with said lever to open said valve, a bolt slidably mounted on said casing and having a stud, another electromagnet mounted on said casing and comprising a spring-pressed armature provided with a projection, said armature adapted to coöperate with said bolt to 80 lock said valve in open position, a pressure gage mounted on said casing and having a rotatably mounted indicator and an index hand, and an electrical connection between 85 said gage and said last named electromagnet whereby when said index hand makes contact with said indicator, said projection coöperates with said stud to draw said bolt and unlock said valve. 90

3. In a device of the class described, a casing having an inlet port and an outlet port, a valve, a seat for said valve located between said ports, a lever pivoted in said casing, a connection between said lever and said valve, an electromagnet mounted on said casing 100 and having a spring pressed armature provided with a projection, said projection adapted during the downward movement of said armature to engage said lever to open said valve, a bolt slidably mounted on said 105 casing and having a stud, another electromagnet mounted on said casing and comprising a spring pressed armature provided with a projection, said armature adapted to coöperate with said bolt to lock said valve in 110 open position, a pressure gage mounted on said casing and having a rotatably mounted indicator and an index hand, and an electrical connection between said gage and said last named electromagnet whereby when 115 said index hand makes contact with said indicator, said armature is retracted and during its backward movement said projection coöperates with said stud to draw said bolt and unlock said valve. 120

Signed by me this 19th day of July, 1912.

EDWARD K. PARKER.
